UNITED STATES PATENT OFFICE

WILLIAM J. MORSE, OF ATTLEBORO, MASSACHUSETTS

COMBINED COLLAR AND NECKTIE HOLDER

Application filed March 20, 1930. Serial No. 437,410.

This invention relates to a combined collar and necktie holder, and has for its object to provide a holder that will grip and hold the wings of the collar properly about the tie and that will also engage the tie and hold the same in proper position between the wings of the collar.

My invention further consists in the forming of a combined collar and necktie holder 10 with oppositely-extending arms, each arm having a collar-gripping jaw and that portion of the holder connecting the arms being arranged to engage the necktie to hold the same in proper adjusted position relative 15 to the collar.

The invention further consists in forming this combined collar and necktie holder from a length of wire folded at its middle portion to embrace or be looped about the necktie, 20 and the ends of the wire being arranged to extend in opposite directions, each having a cooperating jaw to resiliently grip the wings of the collar.

With these and other objects in view, the 25 invention consists of certain novel features of construction, as will be more fully described, and particularly pointed out in the appended claims.

In the accompanying drawings:

30 Fig. 1 is a front view of a collar with a necktie applied thereto, and showing my combined collar and necktie holder as applied to a collar and to the necktie.

Fig. 2 is a front view of the collar holder 35 removed from the collar.

Fig. 3 is a top edge view of the combined collar and necktie holder, showing the collar-gripping jaws and the loop for embracing the necktie.

40 It is found in practice that the wings of a turned down collar, particularly the soft type of collar, are apt to spread excessively when the necktie is applied to the collar; and also that the necktie itself is apt to move 45 about and get out of its proper central adjusted position between the collar wings. Therefore, to correct this and hold both the collar wings and the necktie in proper adjusted positions, I have provided a single holder member which is formed to grip the

wings of the collar to prevent them from spreading away from the necktie and to also embrace the necktie and retain it in proper adjusted position between the wings of the collar; and the following is a detailed description of the present embodiment of my invention and showing one construction of holder by which these advantageous results may be accomplished:

With reference to the drawings, 10 designates the usual turned-down collar which is provided with the usual spaced wings 11 between which is mounted the ordinary four-in-hand tie 12 having the usual knot 13 which extends between the collar wings.

55 In order to retain the wings of this collar snugly up about the tie and to also at the same time retain the tie in proper adjusted position relative to the collar wings, I have formed a combined collar and necktie holder from a length of wire, that shown being of the flat type of wire which is capable of receiving the desired ornamentation along its face. The middle portion of this length of wire, I have folded into ring or loop shape, as at 14, to embrace or partially surround the tie at the point just below the knot thereof. These portions of the wire to the rear of this loop extend around behind the knot of the tie, then upward as at 15 for a substantial distance and then outwardly as at 16 in opposite directions to form collar-embracing arms.

80 Suitable collar-gripping jaws may be formed to cooperate with these arms, that shown being of a separate piece of stock, as best illustrated in Fig. 3, which provide resilient fingers 17, riveted at one end as at 18, to the arms, the outer ends 19 of these fingers 85 extending preferably beyond the extremities of the arms and rearwardly at an angle thereto, forming an entering mouth 20 between them into which the opposite edges of the collar wings may be inserted and gripped 90 to retain these collar wings in proper adjusted position about the necktie.

95 The above describes one specific construction by which cooperating collar-engaging jaws may be formed on the holder, but any 100

other suitable construction of gripping jaws may be employed.

My improved holder arranged to retain both the collar and necktie is very simple in construction and is ornamental in its appearance and by its use both the collar and the necktie may be retained in proper adjusted positions, the extent to which the tie-engaging portion of the holder shall be positioned below the collar-gripping arms may be varied to suit different requirements.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

- 20 1. A combined collar and necktie holder, comprising a central necktie holding portion and a pair of oppositely-extending arms, each being provided with collar-gripping jaws.
- 25 2. A combined collar and necktie holder formed of a length of wire folded at its middle to engage the necktie, the ends of the wire extending in opposite directions, and each being provided with a cooperating collar-gripping jaw.
- 30 3. A combined collar and necktie holder, comprising oppositely-extending arms, each having a collar-gripping jaw, and that portion connecting said arms being folded in loop form to embrace the necktie.
- 35 4. A combined collar and necktie holder, comprising oppositely-extending arms, each having a cooperating collar gripping jaw, and that portion connecting said arms extending downwardly a substantial distance and arranged to engage the necktie.
- 40 5. A combined collar and necktie holder, comprising oppositely-extending arms, each having a cooperating jaw, and that portion connecting said arms extending downwardly a substantial distance and folded into loop form to embrace the necktie.
- 45 6. A combined collar and necktie holder formed of a length of wire folded at its middle to embrace the necktie, and having portions extending upwardly therefrom and then outwardly in opposite directions providing a collar-gripping arm, and each arm being provided with a cooperating jaw member.

In testimony whereof I affix my signature.
WILLIAM J. MORSE.
